UNITED STATES PATENT OFFICE

HENRY V. EKSTEDT, OF EAST ST. LOUIS, ILLINOIS

DESIGN FOR A KEY HOLDER

Application filed June 1, 1931. Serial No. 40,038. Term of patent 14 years

To all whom it may concern:

Be it known that I, HENRY V. EKSTEDT, a citizen of the United States, residing at East St. Louis, St. Clair County, Illinois, have invented a new, original, and ornamental Design for Key Holders, of which the following is a specification, reference being had to the accompanying drawings, forming a part thereof.

Fig. 1 is a front view of a key holder showing my new design; and

Fig. 2 is a side view of the key holder.

In use, the lower stem portion of my key holder is slipped into the eye of a key as turned in a keyhole to lock a door, and the upper loop portion of the holder engages the shank of the adjacent door-knob, to prevent turning the key while so engaged.

I claim:

The ornamental design for a key holder substantially as shown and described.

HENRY V. EKSTEDT.
